UNITED STATES PATENT OFFICE.

WALTER J. KENNEDY, OF CLEVELAND, OHIO.

FUEL-ECONOMIZING VALVE.

1,144,209.

Specification of Letters Patent. Patented June 22, 1915.

Application filed April 11, 1914. Serial No. 831,301.

To all whom it may concern:

Be it known that I, WALTER J. KENNEDY, a citizen of the United States, and resident of Cleveland, in the county of Cuyahoga and State of Ohio, have invented certain new and useful Improvements in Fuel-Economizing Valve, of which I hereby declare the following to be a full, clear, and exact description, such as will enable others skilled in the art to which it appertains to make and use the same.

The objects of the invention are to provide an automatical gravity controlled valve which will prevent foods from burning and which will also prevent the waste of gas when the cooking utensils are removed from the stove.

The invention comprises the pressure operated valve and the detail construction of the various parts and operating devices hereinafter described, shown in the accompanying drawings and specifically pointed out in the claims.

In the accompanying drawings Figure 1 is a plan view of a stove and burner showing the valve and means for operating the same; Fig. 2 is a rear elevation of the stove showing the valve operated by means of a kettle placed over the valve operating device; Fig. 3 is a horizontal section of the valve; Fig. 4 is an enlarged portion thereof; Fig. 5 is a transverse section on line *a*—*a* Fig. 3; Fig. 6 is a side elevation of the arm which operates the valve showing the universal adjustment therefor; Fig. 7 is a transverse section thereof; Fig. 8 is an end view of the divided ball collar therefor; Fig. 9 is a view of the inner face of one of the divisions of said collar; Figs. 10, 11, 12, and 13 show modified adjusting means for the valve arm; Fig. 14 is a vertical section of a modified form of valve showing the universally adjustable arm therefor; Fig. 15 is an edge view of the fixed disk shown in Fig. 3; Fig. 16 is an edge view of the rotatable disk shown in Figs. 3 and 5.

In these views 1 is a valve casing, 2 is the inlet pipe for gas leading thereto, 3 is the inlet pipe leading therefrom to the burner. 4. 5 is a simple cut off valve in the casing. 6, and 7, Fig. 3 are valve disks one of which 6 is rotatable to admit and cut off the gas flowing through the casing. The other one 7 is fixed and the disks are provided with 55 registering perforations *P*, *P*.

8 is a rod provided with a finger, 9, which

engages the rotatable disk. This rod is elbow shaped and turned downward and at its extremity is provided with an arm 10 that extends above the burner and is provided with the spreading downwardly turned fingers 11, which are normally elevated above the top of the stove when the valve is closed, but are depressed to open the valve when the cooking utensil is placed over the burner. They are turned downward at their tips to permit sliding a cooking utensil thereover.

When the valve is opened it permits the gas to flow but when the weight of the cooking utensil is removed the valve is closed by means of a spring 12, thus automatically cutting off the supply of gas to the burner.

The arm 10 is made universally adjustable upon the rod by means of the universal joint shown in Figs. 6, 7, 8 and 9. Here the end of the arm 10 is preferably of oval shape and is inclosed between the lunular shaped members *m*, *m*, of a collar *R*, forming a ball joint. This ball is inclosed in the clamping ring *R* integral with the depending extremity *r* of the rod 8, a screw *r'* serves to secure the parts rigidly together when the fingers 11, 11, are placed at the desired elevation above the burner. This elevation should be such that the weight of the cooking utensil will depress the fingers, arm, and rod, and will rotate the valve disk to admit fuel gas to the burner the amount of opening being determined by the amount of heat required.

The universal joint enables the arm 10 to be moved vertically to adjust the elevations of the fingers and also to be moved longitudinally of itself to place it in the center of the burner and accommodate itself to the size and shape of the grating over the burner. It also permits of a rotary adjustment to place the ends of the fingers which are downwardly curved upon a common level. Other means for obtaining adjustment of the arm 10 are shown in Figs. 10, 11, 12, 13.

In Figs. 10 and 11 a connecting T-shaped sleeve *T* is employed to connect the rod 8 and arm 10. Set screws *t*, *t*, permit the parts to be secured in any desired position relative to each other.

In Figs. 12 and 13 a sleeve *S* upon the extremity of the rod 8 permits of longitudinal and rotary movements only.

In further description of the valve shown

in Figs. 3, 4, 5, and 6, the casing is shown to be divided into two cylindrical portions A and B. The portion B is screw threaded and adjustably sleeved over the portion A. 5 The fixed disk 7 is secured transversely in the portion B upon a shoulder *b* and the disk 6 is rotatably seated in the portion A upon a shoulder *a*.

To permit the disk 6 to rotate freely without making contact with the wall of the casing it is provided with a pivotal shaft or trunnion 16 which rotates in a pivot opening 17 in the disk 7 and the disk 6 is therefore supported thereon. This structure and the shoulders prevents the gas from passing the disks except when the perforations P come in alinement. 15

The rod 8 is provided with a sleeve 18 which can be secured thereto at any desired 20 angle by means of a set screw 19 and a short arm 9 upon the sleeve enters a small opening 21 formed in the inner face of the disk 6 at a predetermined distance from the pivotal point, and thus determines the amount 25 of movement of the disk when operated by the rod 8.

The perforations P, P in each disk are spaced apart so that they can be entirely opened and entirely closed by rotating the 30 disk 6.

A spring coiled within the valve chamber and engaging the disk at one end and the wall of the chamber at the other end returns the disk to the closed position after 35 the rotation of the rod 8 has opened it.

A pin X inserted in the wall of the casing A engages the slot X' in the disk 6 and limits the movement of the valve in each direction. 40

In Fig. 14 the universal joint for the arm and rod is shown adapted to the operation of a valve V by means of an elongated finger F. This valve is the one described in a prior application Ser. No. 781,112, filed July 45 30, 1913.

The fuel gas is admitted to and cut off from the valve chamber by means of a simple form of cut off valve Z. This valve also controls the admission and cut off of fuel 50 gas to a passage Y which leads to a pilot light y' at the burner. To accomplish this the valve Z is provided with a main transverse passage Z' and segmental passages Z^a, Z^b lead therefrom upon one side of the passage to the pilot light. 55

The valve can be turned to three positions, first, to admit gas to the burner and pilot light simultaneously second, to cut off the supply of gas to the burner but still 60 supply gas to the pilot light, and third, to cut off all passage of gas. The several positions of the valve are shown in Figs. 3^a, 3^b, and 3^c respectively.

In Figs. 1 and 2 automatically acting 65 means are shown for operating the burner to

close or partially close the same without removing the kettle or other cooking utensil from the fire and thus relieve the cook from responsibility, and prevent spoiling the food. 70

This construction is employed in connection with a boiling-kettle and is designed to permit the kettle to rise and operate to close the valve when the water therein has evaporated sufficiently to endanger the food 75 therein.

In these views W is a lever or beam pivoted at *w* in the top of the stove, at one side of the burner. Upon the pivotal shaft W' are secured the downwardly and curved fingers W², W², and upon the opposite side of the burner are secured the correspondingly shaped fingers W³, W³ upon a pivotal shaft W⁴. 80

One set of fingers W² moves with the oscillation of the beam W and the opposite set of fingers W³ is moved by means of the arm W⁵ which is engaged by one end of the beam W as it moves. To the other end of the lever is pivoted the auxiliary beam or lever W⁶ at W⁷ which is provided at one end with a roller W⁸ which moves upon the lower edge E of the top of the stove, and upon the other end of the lever W⁶ is secured the sliding weight W⁹. 90

The weight W⁹ is so adjusted upon its lever that when the kettle K containing the food rests upon the upwardly turned extremities of the fingers W², W³ it is supported thereby above the fingers 11, 11, but 100 when water is added it will fall and press the fingers 11, 11 down and operate the valve to close the same, so as to prevent the food from burning in the absence of the cook, and if a sufficient amount of water is placed in the kettle and the burner carefully adjusted the food can be cooked and the burner turned off without attention from the cook. 105

H is a hook upon which the rod W⁶ can 110 be hung when not in use.

I is a pin upon the lever W against which the lever W⁶ strikes to limit its movement.

The valve is adapted for use with liquids as well as gases. 115

Having described the invention what I claim as new and desire to secure by Letters Patent is:

1. In a valve for a fuel gas burner, a cylindrical valve casing, a stationary disk 120 transversely mounted in said casing, a rotatable disk mounted thereon, said disks provided with equally spaced perforations therethrough, said perforations permitting the passage of gas therethrough when those in one disk are in alinement with those in the other disk, an adjustable rod rotatable in said casing and operatively connected with said rotatable disk, an adjustable arm 125 connected with said rod and a device upon 130

said arm engageable by a cooking utensil when placed over said burner.

2. In a valve for a fuel gas burner, in combination, a casing, a disk secured therein, a second disk rotatable therein said disks provided with perforations, the perforations in one disk alined with the perforations in the other disk when the valve is open, a device for rotating said rotatable disk, said device adapted to be centrally adjusted to said burner extending above said burner and depressible by means of a cooking utensil placed thereon, to close said valve and raise said disk operating device when the 15 cooking utensil is removed from said burner.

3. In a valve for a fuel gas burner, in combination, a casing, a rotatable disk therein provided with a series of outlet openings, a fixed seat upon which said disk 20 is rotatable, said seat provided with corresponding perforations, a rotatable rod for operating said disk, means located above said burner adapted to be adjusted with respect to the center of said burner, and device 25 pressible by the weight of a cooking utensil, and means for automatically returning the disk when said rod is released.

4. In a fuel economizing valve for a stove burner, a valve casing, a rotatable valve 30 therein, a rotatable rod in said casing, operatively connected with said valve, an arm provided with extensions projecting above said burner, a universally adjustable joint connecting said rod, and arm, whereby the 35 position of said extensions can be adjusted relatively to their location above said burner.

5. In a fuel economizing valve for a stove burner, a valve casing, a rotatable valve therein, a rotatable member in said casing 40 operatively connected with said valve, an arm for said rotatable member provided with extensions adapted to project above said member and to be depressed by a utensil placed thereon, a universal joint connecting 45 said rotatable member and arm, for the adjustment of said arm relatively to said burner, and means for automatically elevating said arm and closing said valve when the weight is removed from said arm.

50 6. In a fuel economizing valve for a stove burner, a casing, a rotary valve therein, said valve and casing having corresponding inlet openings, a rotatable rod in said casing means on said rod for engaging said valve 55 to rotate the same, a depressible adjustable arm connected with said rotatable rod, said arm having an extension rising above said burner, when said valve is closed, and means for closing said valve and raising said extension to place, when said extension is released.

7. In a valve operating device for a stove burner, the combination with said valve and casing, a rod rotatably mounted in said casing, an arm operatively connected with said

rod, and having universal movement thereon, an extension of said arm provided with laterally and downwardly extending fingers and adapted to project above said burner when said valve is closed, and to be depressed to open said valve when a cooking utensil is placed over said burner, and an auxiliary weight controlling device for supporting said cooking utensil and food therein, said weight controlled device permitting said cooking utensil to depress said fingers when the weight of said food has been reduced by action of the heat from said burner.

8. The combination with a depressible valve controlling arm located above a burner and a fuel inlet valve controlled by the movement of said arm, of a pivoted beam and an auxiliary weight controlled beam pivoted thereon, and fingers adapted to engage a cooking utensil containing liquid and operated by said beams, said fingers being depressed by the weight of said cooking utensil and contents, permitting said utensil to engage and depress said depressible valve 80 controlling arm, said fingers and weighted lever acting to raise said utensil and permit said depressible arm to rise, when the weight of said utensil and contents becomes less, and means for raising said arm and closing 95 said valve.

9. The combination with a stove burner, a fuel valve, a depressible valve controlling device for operating said valve projecting above said burner when said valve is closed, a weight controlled beam lever device adapted to be depressed by a cooking utensil over said burner, said utensil also depressing said valve operating device, said weight adjustable upon said beam lever, said weight adapted to operate said beam lever to raise said cooking utensil and permit the rising of said valve controlling device, when the weight in said cooking utensil is reduced.

10. The combination with a valve controlling device for a stove burner, a lever pivoted in said stove, vertical fingers extended above said burner and operated to rise and fall by the movements of said lever, a second weight controlled lever pivoted to 110 the first named lever and provided with an extension and a roller pivoted upon said extension and a horizontal guide for said roller on said stove.

11. The combination with a stove and burner, of a supply pipe leading to said burner, a valve in said supply pipe and a disk rotatable therein, a rotatable rod in said casing operatively connected with said disk, said rod having an integral downwardly turned extremity, and an arm adjustably secured in said downwardly turned extremity, said arm having its inner extremity elevated above said burner.

12. The combination with a stove and 130

burner and a supply pipe leading to said burner, of a valve casing in said supply pipe and a disk rotatable therein, a rod operatively connected with said disk and having an integral downwardly turned extremity, an arm extending from said rod and having its inner extremity elevated above said burner, said inner extremity of said arm provided with downwardly turned members

permitting a cooking utensil to slide thereover, and means for adjustably attaching said rod and arm together.

In testimony whereof, I hereunto set my hand this 26th day of March 1914.

WALTER J. KENNEDY.

In presence of—

Wm. M. MONROE,
AUGUSTUS N. BELL.
